UNITED STATES PATENT OFFICE.

JOHN C. JOHNSON, OF UNIONTOWN, PENNSYLVANIA.

BAG-FILLER.

SPECIFICATION forming part of Letters Patent No. 617,961, dated January 17, 1899.

Application filed May 2, 1898. Serial No. 679,497. (No model.)

To all whom it may concern:

Be it known that I, JOHN C. JOHNSON, a citizen of the United States, residing at Uniontown, in the county of Fayette and State of Pennsylvania, have invented certain new and useful Improvements in Bag-Fillers; and I do hereby declare the following to be a full, clear, and exact description of the invention, such as will enable others skilled in the art to 10 which it appertains to make and use the same.

This invention relates to an improvement in bag-filers and is especially adapted for grocers' use. Its object is to produce a device simple and economical in construction 15 and operation, easily and readily assembled for use and taken apart for transportation, &c., and provided with means whereby the bag is securely held in position to be filled and readily removed therefrom.

20 To these ends the invention consists of a hollow standard made, preferably, of pipe and screwed into the center of a base of heavy metal, whereby said standard is held in a vertical position. Over the upper end of said 25 standard is detachably secured a cap containing a pulley which projects slightly from one side thereof and serves to support and guide a cord secured at one end to a sliding bracket and at the opposite end to a weight adapted 30 to travel vertically within said hollow standard. The bracket to which said cord is attached consists of a sleeve cylindrical in form and having projecting therefrom near its lower end a horizontal arm forked or U-shaped 35 at its outer end and supported by means of a second arm projecting downward from the upper end of said sleeve. A funnel of peculiar construction is adapted to be held between the forks of the arm, said funnel being 40 provided with a circular flange for the purpose hereinafter described.

In the accompanying drawings, forming part of this specification, Figure 1 is a perspective view of the filler with the bag attached and resting upon scales. Fig. 2 is a central vertical section through the bag-filler. Fig. 3 is a detached view showing the means for securing a bag to the arm. Fig. 4 is a view of the funnel detached.

45 Referring to said figures by letters of reference, A is a base of any desired form and composed of heavy or weighted metal. Said

base is provided through the center with a threaded opening a, adapted to receive one of the threaded ends of the hollow standard 55 B, which consists, preferably, of a section of gas-pipe, although I do not confine myself to this mode of attachment. Screwed or slipped down upon the upper end of said standard is a cap C, within one side of which is pivoted 60 a pulley D, adapted to project slightly beyond the outer and inner surfaces of said cap, as shown. Slidably mounted upon the slide B is a sleeve E, preferably of the form shown. The lower end of said sleeve or 65 parts thereof may be flared outwardly, as shown, while the upper end may be provided with a lug or slightly-flared portion e.

Encircling and fitting closely to the sleeve E, near the upper and lower ends thereof, 70 are the substantially circular ends f g of the support F and arm G of the bracket, respectively. At the points f' g', however, said ends are preferably a sufficient distance from the sleeve E to permit the passage thereunder 75 of the lug e for the purpose hereinafter described. The ends G' of the arm G, which is preferably formed of twisted wire, extend outward horizontally, forming a substantially U-shaped fork, as shown. Said fork is adapted 80 to receive a funnel H, provided at a point above its lower end with a flange h, which rests thereupon. The ends h' of said flange are separated to present a smooth surface to permit the operator to press the bag against 85 the funnel between the ends of the flange to hold the bag in position until placed upon the forks. Secured to said supporting-arm F and passing upward therefrom over the pulley down into the standard is a cord I, attached 90 at its inner end to a weight J, as shown. Said weight is such as to balance the weight of the bracket and funnel and permit the same to be moved to and remain stationary at any point upon said standard. 95

The operation of the device will be obvious. The parts which are separable are placed together by first attaching the standard to the base-plate and slipping the collar E thereover. Ends or loops f and g are then placed over 100 the bracket by passing the points f' g' over lug e and then turning the same to one side, thereby securely retaining the arms to the sleeve, as will be obvious. In practice, how-

- ever, I secure the arm to the sleeve by clamping the same thereto by twisting the wire of which they are composed, as shown in the drawings. Cord I, which is fastened to the 5 support F, is then passed over the pulley D and attached to weight J, said weight being placed in the standard and the cap C secured thereupon. The collar and bracket may then be raised or lowered, as desired.
- 10 In filling the bag the upper sides thereof are placed over the flange h of the funnel H, the loose portion of the bag being gathered in front to permit the operator to place it within the U-shaped fork of arm G, said 15 flange and funnel serving as a weight to hold the upper edge of the bag securely between the flange and the fork. The bag having been filled, the operator raises the funnel from the bag by sliding the bracket upwardly.
- 20 The standard may be attached to a platform or to the frame of an ordinary platform-scales. If attached directly to the platform, allowance should be made for the weight of my device by deducting its total weight or 25 adjusting the scales to represent the weight of the attachment.

It is obvious that the funnel is also capable of use for all purposes for which a funnel is desired.

In the foregoing description I have shown 30 the preferred form of my invention; but I do not confine myself thereto, as I am aware that modifications may be made therein without departing from the spirit or sacrificing the advantages thereof, and I therefore re- 35 serve the right to make such changes as fairly fall within the scope of my invention.

Having thus fully described my invention, what I claim, and desire to secure by Letters Patent, is—

40 A bag-filler consisting of the standard, a detachable cap thereon, a pulley mounted in said cap, a sleeve mounted on said standard, a counterpoised, forked bag-supporting bracket, loops at the inner ends of said bracket 45 adapted to encircle the sleeve, a lug on said sleeve adapted to lock the loops thereon, and a funnel separate from, and adapted to rest upon, the forks of the bracket, said funnel having a horizontal flange, formed thereon 50 above its lower end, substantially as described.

In testimony whereof I affix my signature in presence of two witnesses.

JOHN C. JOHNSON.
